(57) **CLAIM**

The ornamental design of a safety blood collection needle device, as shown and described.

DESCRIPTION

FIG. 1 is a perspective view of a safety blood collection needle device having a patient needle guard disposed over a needle, a non-patient needle guard, and a shield in an initial position in accordance with an embodiment of the present invention;

FIG. 2 is a top view of the safety blood collection needle device of FIG. 1;

FIG. 3 is a left side view of the safety blood collection needle device of FIG. 1;

FIG. 4 is a front view of the safety blood collection needle device of FIG. 1;

FIG. 5 is a rear view of the safety blood collection needle device of FIG. 1;

FIG. 6 is a right side view of the safety blood collection needle device of FIG. 1;

FIG. 7 is a bottom view of the safety blood collection needle device of FIG. 1;

FIG. 8 is a perspective view of the safety blood collection needle device of FIG. 1 having the patient needle guard removed and the shield in a retracted position in accordance with an embodiment of the present invention;

FIG. 9 is a top view of the safety blood collection needle device of FIG. 8;

FIG. 10 is a left side view of the safety blood collection needle device of FIG. 8;

FIG. 11 is a front view of the safety blood collection needle device of FIG. 8;

FIG. 12 is a rear view of the safety blood collection needle device of FIG. 8;

FIG. 13 is a right side view of the safety blood collection needle device of FIG. 8;

FIG. 14 is a bottom view of the safety blood collection needle device of FIG. 8;

FIG. 15 is a perspective view of the safety blood collection needle device of FIG. 1 having the patient needle guard removed and the shield in a shielded position in accordance with an embodiment of the present invention;

FIG. 16 is a top view of the safety blood collection needle device of FIG. 15;

FIG. 17 is a left side view of the safety blood collection needle device of FIG. 15;

FIG. 18 is a front view of the safety blood collection needle device of FIG. 15;

FIG. 19 is a rear view of the safety blood collection needle device of FIG. 15;

FIG. 20 is a right side view of the safety blood collection needle device of FIG. 15; and,

FIG. 21 is a bottom view of the safety blood collection needle device of FIG. 15.
